CLAIM

The ornamental design for a handle for interchangeable brush heads, as shown and described.

DESCRIPTION

FIG. 1 is a perspective view of a handle for interchangeable brush heads, showing our new design;

FIG. 2 is a rear elevation view of the handle for interchangeable brush heads;

FIG. 3 is a front elevation view of the handle for interchangeable brush heads;

FIG. 4 is a left side elevation view of the handle for interchangeable brush heads;

FIG. 5 is a right side elevation view of the handle for interchangeable brush heads;

FIG. 6 is an enlarged top plan view of the handle for interchangeable brush heads;

FIG. 7 is an enlarged bottom plan view of the handle for interchangeable brush heads; and,

FIG. 8 is a perspective view of the handle for interchangeable brush heads, shown in an environment of use.

The broken lines in the drawings are for the purpose of depicting environment and form no part of the claimed design.

1 Claim, 5 Drawing Sheets
